CLAIM

The ornamental design for a magnetic detacher as shown and described.

DESCRIPTION

FIG. 1 is a front right perspective view of a magnetic detacher showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken lines shown represent the portions of the magnetic detacher that form no part of the claimed design.

1 Claim, 7 Drawing Sheets
